UNITED STATES PATENT OFFICE.

ERNEST D. SIMONS, OF CHESHIRE, CONNECTICUT, ASSIGNOR TO SCOVILL MANUFACTURING COMPANY, OF WATERBURY, CONNECTICUT, A CORPORATION OF CONNECTICUT.

FASTENER SLIDE.

Application filed February 29, 1928. Serial No. 257,973.

Waterproof overshoes, of the well known types of arctics and galoshes, have been provided with straps, of the same material as the uppers, on which are mounted fastening members cooperating with complementary fastening members fixed to the opposite side of the shoe opening from that on which the straps are secured; and in some instances the fastening members on the straps are made in 5 members cooperating with complementary fastening members fixed to the opposite side of the shoe opening from that on which the straps are secured; and in some instances the fastening members on the straps are made in 10 the nature of slides which may be adjusted on the straps in order to provide for securing a substantially tight closure of the opening. In the instances of such adjustable slide fastenings to me known, the slides have transversely slotted openings for the passage of the straps, and in all such instances the constructions are such as to cause the strap to bulge within the confines of the slides in an unsightly and inconvenient manner. In order 15 to secure such slides in adjusted positions on the straps, the slides have been provided with a prong extending off from the center bar in such way as to dig into the material of the strap. These straps when made of material 20 like that in the uppers of the shoes, have the outside material folded over with its edges meeting in a center line, and where a single prong is used, it is located on the slides in a line with this joint and has a tendency to 25 wear the strap at the point of least resistance. When using the one-pronged slides, those who assemble them on the straps must be careful to locate the prong in such position 30 as to ensure the engagement of the prong with the strap and resist the slipping of the slides from adjusted position.

The object of the present invention is to provide a slide that will not cause the strap to bulge, and which has roomy slots for the easy 40 passage of the strap in assembling and to avoid the bulging of the strap, and having a plurality of prongs on both edges of the center bar, located out of the line of the meeting edges of the strap so as not to engage the 45 strap in the line of said meeting edges, but on opposite sides thereof, and also to provide that the slide may be assembled on the slot regardless of the direction of strain; or in other words, so that the prongs will engage the 50 strap to hold the slide in adjusted position regardless of which way the slide may be assembled on the strap.

The invention consists of a fastener slide, having a center bar located below the plane of

the frame, and having roomy slots on opposite sides, the center bar carrying the fastening element, which latter may be the head or stud or the socket member of a snap fastener; said center bar having on opposite sides of the fastening element upwardly extending 55 prongs pointing in opposite directions toward opposite ends of the slide and serving to engage the strap which ever way the slide may be placed upon the strap and thus to hold the slide in adjusted position, secure against 60 the strains in use, as I will proceed now to explain more fully and finally claim.

In the accompanying drawings illustrating the invention, in the several figures of which like parts are similarly designated, Figure 1 70 is a perspective view illustrating one embodiment of the invention and applied to a strap which is shown partly in full and partly in dotted lines. Fig. 2 is a plan view of one side of the slide, and Fig. 3 a similar view of the 75 reverse side. Fig. 4 is a side elevation showing the strap in dotted lines, these four figures illustrating the invention as applied to a head or stud member of a snap fastener. Fig. 5 is a top plan view, and Fig. 6 a plan 80 view of the reverse side of a slide embodying the socket member of a snap fastener, and Fig. 7 is a section on line 7—7 of Fig. 5.

One method of forming waterproof straps for arctics and galoshes and similar overshoes, consists in folding over the material 85 1 upon an adhesive strip 2 and the parts adhered, and having the edges of the part 1 meet substantially in the longitudinal center of a strap, as indicated at 3. Of course, the 90 invention is not limited to its use in connection with such a strap and said strap is shown for illustrative purposes. The strap is designed to receive a fastener slide, which may be adjusted thereon so as to close the opening 95 in the upper of the shoe to such an extent as to make the shoe comfortable to the wearer.

The slide comprises the side frame elements 4, between which is arranged the center bar 5, and this center bar is adapted to receive or be provided with a snap fastener element, such as the head or stud 6 which projects outwardly therefrom. The center bar is provided on opposite edges with the upstanding prongs 7 pointing in opposite directions and arranged out of line with the fastener element 6. The frame elements 4 are connected with the frame elements or end bars 8 by

means of the aforementioned offsets, so that the center bar 5 and end bars 8 are in substantially parallel horizontal planes and are spaced apart sufficiently to permit the passage between them of the strap without materially bulging the strap at the point of connection, but on the contrary permitting the strap to lie substantially flat, as indicated in Figs. 1 and 4. As shown in Figs. 1 and 4, the 10 prongs 7 enter the strap and prevent the slipping of the slide on the strap after it has been once fixed in adjusted position.

The provision of the oppositely inclined pairs of prongs admits of the application of the slide to the strap either end on, as it is apparent that the prongs on either side of the center bar will resist the strains of use and prevent slipping of the slide in one direction.

Between the center bar and the end bars 20 8, are slots 9, of considerable height and width so as to provide for the ready application of the slide to the strap. As will be seen by reference to Figs. 1, 2 and 3, the slots extend beyond the ends of the center bar and thus 25 cooperate with the spacing apart of the center bar and end bars to provide roomy slots hereinbefore referred to. The center bar and the end bars are connected at the sides of the slide by means of the offsets 10.

It will be observed that the center bar is substantially flat, so as to lie as close to the strap as possible and thus avoid the bulging of the strap.

As shown in Figs. 5, 6 and 7, the shape of 35 the slide may be varied and still retain some or all of the features previously described, but with the center bar having a resilient or non-resilient socket member 11 applied to or formed therewith. With this construction 40 there is no need of spacing the end bars 12 from the center bars 13 as far as shown in the slide of Figs. 1 to 4. Moreover, the frame, composed of the end bars 12 and side bars 14, may have a substantially rectangular outline with the parts concaved as shown at 45 15 in Figs. 6 and 7. The center bar 13 as in the case of the slide shown in Figs. 1 to 4, has the upstanding pairs of prongs 16 arranged on opposite sides of the snap fastener element 11 and projecting from the center bar in opposite directions so as to impale the slide on the strap whichever way the slide may be applied to the strap. 17 are the slots for the passage of the strap.

Where, as in prior constructions, a single 55 central prong has been used on the center bar of the slide for use on the straps of arctics, galoshes and other overshoes, the central arrangement brings the prong substantially 60 into the line of weakness of the strap, indicated at 3, and not only tends to open the strap covering, but also prevents an effective hold on the strap. Moreover, with one or any other number of prongs located on one 65 side only of the center bar, the same difficulty occurs of requiring the workmen to place the slide on the strap in the one and only direction in which the prongs become effective.

The use of prongs on both sides of the center bar assists the operator in mounting the slides on the strap, and it is not necessary for him to look at each slide to make sure that it is mounted with the prongs in the proper direction. It is also to be noted that the use 75 of two prongs facing in the direction of the tendency of the slot to slip, dig into the material of the strap at two points and thereby effect a better holding quality than one prong.

Variations in the details of construction 80 are permissible within the principle of the invention and the scope of the claims following.

What I claim is:—

1. A fastener slide, having side and end bars, a center bar spaced from the end bars to provide roomy slots for the substantially flat passage of a strap on which the slide is mounted, a fastener element on the center bar, and a plurality of upstanding prongs projecting from opposite sides of the center bar and in opposite directions and toward the opposite ends of the slide, so as to engage the strap whichever way the slide may be applied to the strap. 85 90 95

2. A fastener slide, having side and end bars, a substantially flat center bar having a fastener element, the side and end bars being spaced apart and connected by offsets, there being roomy slots between the center bar and the end bars and the offsets, and upstanding prongs on both edges of the center bar and on opposite sides of the fastener element and inclined toward the opposite ends of the slide. 100 105

In testimony whereof I have hereunto set my hand this 28th day of February, A. D. 1928.

ERNEST D. SIMONS.
